Inventor

James B. Slinn

UNITED STATES PATENT OFFICE

JAMES B. SLINN, OF BONAPARTE, IOWA

FLYING MACHINE

Application filed July 23, 1928. Serial No. 294,675.

My invention relates to flying machines of the ornithopter type and in the present instance illustrated as a toy but the principle is adaptable to machines of the man carrying form.

The object of the invention is to provide a flying machine having a simple but thoroughly efficient form of mechanism for the movable wings thereof so arranged, constructed, and mounted as to obtain novel action of the said wings.

That my invention may be fully understood, the accompanying drawing is provided wherein:

15 Figure 1 is a plan of the flying machine of my invention.

Figure 2 illustrates on a larger scale, in perspective, the mechanical driving elements for the wings.

20 Figure 3 shows the rear portion or tail of the machine in perspective.

Figure 4 is a plan on a larger scale of parts shown in Figure 1.

25 Figure 5 is a plan of a crank-shaft, and

Figure 6 shows in perspective parts illustrated in Figure 2.

The machine includes a body 1 supported on which, at its rear end and at opposite sides are tail members 13. At its forward end the body 1 has erected upon and attached to it a standard 6 which in this instance has upwardly and outwardly divergent extensions or arms 18 supporting a plate 9 lying transverse to the longest measurement of the body 1 and having a bearing 15 at each end. Each bearing carries therein part of a wing-spar 10, the latter lying at the leading edge of a wing 12. Said spar beyond the bearing is extended downwardly forming a bell-crank 16. Affixed to the plate 9 and extending rearwardly therefrom in a divergent manner is a pair of ribs 11 adapted to vibrate vertically rearward of the plate and are of a length determining the fore and aft measurement of the said wings 12, the latter being extended from the spars 10 at the bearings 15 back to the free ends of said ribs 11, the material of the wings hinging, so to speak, along and between the 50 positions named, and the rear edges of the

wings describe curved lines from the rear free ends of the ribs to the extremities of the spars 10. Also, the material of the wings extends between the ribs 11 and attached thereto forming a "plane" 20, Figures 1 and 2.

Erected on the body 1 rearward of the standard 6 is a standard 4 forming a bearing for a crank-shaft 8 which latter also has a bearing in a bushing 7 of the said standard 6, said shaft terminating forward of the latter in a crank 8'. Between the two standards 4 and 6 the shaft 8 has two opposed cranks 3 each of which is connected by a pitman 5 in suitable manner with the free end of one of the bell-cranks 16. The rear end of the shaft in this instance terminates in a hook 17 to receive over it one end of a rubber band 2, the other end of the latter engaging over a similar hook 14 erected on the body 1 in the rear.

It is clear that by means of the crank 8' the elastic member or band 2 may be placed under torsional stress which when liberated will transmit rotary movement to the shaft 8, in consequence of which the wings 12 through the cranks 3, pitman 5 and parts 16 and 10, will receive a more or less violent vertical action, both wings rising and falling at the same time due to the relation of the cranks. The springy nature of the ribs 11 coupled with the fabric composing the wings rotating about the spars 10 changing the angle of attack of the wings and plane 20, and the air is compressed between the wings 12 on their downward strokes. The rear edges of the wings move upwardly on the down stroke and downwardly on the up stroke and this action together with a slight consequent vertical movement of the plane 20, which is wider at its rear end, act as propelling adjuncts.

The more or less flexibility of the standard 6 carrying the plane 20 permits a forward and back action during wing movement causing the latter to change the angle of attack by moving slightly forward in the down stroke and backward in the upstroke, assisting in driving the machine forward.

Changes of minor nature may be made in

my flying machine structure without departing from the spirit of the invention or the meaning of the appended claims.

I claim:

5. 1. A flying machine of the class described including in its construction a body portion, supporting means mounted thereon, a shaft journaled in said means and having a crank at opposite sides of the axis thereof, power means connected to the shaft, a pair of wings each including a wing spar hingedly mounted on a part of the said supporting means, a lever rigid with the hinged portion of the wing spar, and a rod connecting each lever with one 10 of said cranks.
15. 2. A flying machine of the type described including a body portion, supporting means erected thereon near the forward end, a substantially flat vane affixed at one end to said 20 means and extending rearward therefrom and free to flex, wings hingedly connected to the supporting means and each hinged to a side edge of the vane, and means including a power source for operating the said wings.
25. 3. A flying machine of the type described including a body portion, a support erected thereon adapted for a slight vibratory movement in a fore and aft direction, a vane secured at one end to the support, extending 30 rearward therefrom and having an unsupported rear end and free to vibrate, a wing hingedly connected to each side edge of the vane, and power means operatively connected to the wings.
35. 4. A flying machine of the type described including a body portion, a support erected thereon, a flexible vane having a narrow and a broad end and attached at its narrow end to the support, its broad end being unsupported rearward from the support and free to flex, a wing hingedly connected to each side edge of the vane, and power means operatively connected to the hinged edges of said wings.
40. 5. A flying machine of the type described comprising a body portion having a tail member, a support erected on the forward end of the portion, a vane attached at one end to the support and disposed in a horizontal plane 45 and having a rear end free to vibrate vertically, a wing hingedly mounted at each of the two opposite side edges of the vane, a shaft supported by the body portion and having a pair of cranks opposed to each other, power means connected with the shaft, and members connecting the cranks and the hinged edges of said wings.
50. 6. A flying machine of the type described including a body portion, an upstanding support fixed thereon and free to flex, a flexible vane attached at its forward end thereto and unsupported at its rear end, a wing hingedly connected at each side edge of the vane, and power means operatively connected to the 55 wings.
7. A toy flying machine including in its construction a support, a vane attached to the support extending rearward therefrom, a wing hinged to each side edge of the vane including a member rigid therewith, a shaft journaled on the support having two cranks in opposed positions, a connecting-rod extending between and connecting each crank with one of the said members, and a power source connected to and exerting rotative action to said shaft.
8. A toy flying machine including in its construction a body portion, a support erected on the forward part thereof, a pair of flexible ribs affixed at one of their ends to the support and extending rearward and unsupported at their rear ends and free to vibrate, a vane extending between and affixed to the ribs, and a wing attached to each rib outward from the vane.

In testimony whereof I have signed my name to this specification.

JAMES B. SLINN.
